UNITED STATES PATENT OFFICE.

PAUL HORACEK, OF GERMANTOWN, PENNSYLVANIA.

BOOKMARK.

Application filed April 3, 1926. Serial No. 99,642.

This invention relates to improvements in book marks, and more particularly to a device embodying a page separating arm with the body portion therefor providing a certain amount of torsional tension to the arm, and with the body portion adapted to be detachably secured to a book cover for indicating the last page read upon the re-opening of a book. The principal object of the invention is to provide a book mark of a single length wire formation, which is particularly adapted for use on books, magazines, and other periodicals of like character, for retaining and indicating the next following page by separating the preceding pages therefrom, and further provided with means for imparting torsional tension to the device for holding a book in open position.

Another object of the invention is to provide a book mark as specified, which is simple in construction and operation, cheap to manufacture, readily applied to a book, magazine, or the like, and one which will not injure or obstruct the turning of the pages which are held separated by the extended arm comprising the book mark.

Other objects of the invention will appear in the following detail description, and in the accompanying drawing, wherein:

Figure 1 is a perspective view of a book in open position, with the book mark attached thereto in operative position.

Figure 2 is a similar view with only the rear cover of a book extended in open position, indicating the manner of attaching the device thereto.

Figure 3 is a plan view of the device per se.

Figure 4 is an end view of the device per se.

Figure 5 is a plan view of a modified form of the device.

Referring more particularly to the drawing, the invention comprises a single length of wire 10 preferably spring wire, bent upon itself intermediate its ends 11 and 12, to provide a depending tongue 13 with the free end portions 14 and 15 extended upwardly. The free end portion 14 is bent at right angles, as at 16, and extends laterally to the right-hand side of the tongue 13, to form the arm 17, and again bent at right angles, as at 18, to provide the depending page engaging finger 19 with the extreme free end thereof bent upon itself to provide the rounded end 20 for preventing injury to the pages of a book, or the

like. The free end portion 15 is bent upon itself at a point parallel with the laterally extending arm 17, and continues downward at an acute angle for a distance approximately one-third the length of the tongue 13, whereupon another bend is made at a point indicated at 21. The end portion 15 is then extended across and to the rear of the tongue 13, to a point indicated at 22, where a similar bend occurs for extending the wire upwardly at an acute angle to a point adjacent the bend indicated at 16, and parallel with the arm 17, where the wire is again bent upon itself, as at 23, for extending the remaining end 11, of the end portion 15, downwardly, parallel with and adjacent the left-side of the tongue 13 to a point intermediate the arm 17, and the laterally extended lower portion 24, comprising the attaching clip 75 formed on the tongue 13.

The extreme point 25 of the end portion 15, is finally bent at right angles to the tongue 13 and overlaps the end portion 14 comprising the left side of the tongue 13. A tie plate 26 is secured to the upstanding end portion 14 and 15 intermediate the lower clip portion 24, and the bottom end of the tongue 13 by rolling the ends 27 of the plate 26 around the end portions 14 and 15, for providing the arm 17 and the depending finger 19 thereof, with sufficient torsional tension for holding down the pages of a book without interfering with the turning of the pages thereof.

The modified form of the invention as illustrated in Figure 5 of the drawing, comprises a metal stamping 10' which is blanked out from a sheet of metal, and formed to simulate the configuration of the device, as shown in the preferred wire form.

From the foregoing description taken in connection with the accompanying drawing, it will be readily apparent that I have provided a simple and novel type of book mark which is readily attached to a book cover, and which permits the pages to be turned to the left in the usual manner without tearing or otherwise injuring the pages, and while I have shown and described my invention, I do not however, limit myself thereto, except as set forth in the claims hereunto appended.

What I claim is:—

1. A book mark comprising a single length of wire bent intermediate its ends to provide a tongue, one side portion of said tongue

bent centrally at right angles to form a laterally extending arm, the outer end portion of said arm bent at right angles to said arm to provide a depending page engaging finger, the extreme end of said finger bent upon itself to form a rounded loop, the opposite side portion of said tongue bent upon itself to extend downwardly at a point parallel with said arm and by a plurality of successive bends formed into a substantially frustro-conical clip, said clip depending from the free end of said tongue adjacent thereto, the free end of said opposite side portion terminating in a depending portion parallel with and adjacent the opposite side portion of said tongue, the extreme end thereof bent at right angles to overlap the said opposite side portion of said tongue, to impart a tortional tension to said arm and finger, and 20 a tie plate secured to and intermediate the side portions comprising said tongue to maintain said side portions in spaced parallel relation.

2. A book mark constructed from a single 25 length of wire and comprising a pair of loops to straddle the back of a book, each of said loops having side members, the upper end of one of the said members of the loop engages with the inner face of the book back 30 having a right angle extending arm terminating in a right angle extending finger for engagement between the pages of a book, the upper end of the corresponding side member of the other loop, which engages with the 35 outer face of the book back having an arm

parallel with the side member which has the first arm, the extremity of the second arm having an offset bend terminating in a lateral extension overlying the side member having the first arm to assist in retaining the 40 last mentioned side member in proper position when a tortional tension is imparted to the first arm when placed in engagement between the leaves of a book.

3. A book mark comprising a pair of loops 45 substantially in parallelism and adapted to straddle the back of a book and which comprises side members, one end of one of the side members of one of the loops having an arm at right angles to the loop and terminating in a finger at its extremity to engage between the pages of the book, one end of one of the said members of the other loop having an arm substantially parallel with the side member having the first arm, the second arm terminating in a lateral extension with an offset portion to overlie one of the said members which has the first arm to retain the side member in position when a tortional tension is imparted to the first arm, 60 and a tie plate secured to the side members of one of the loops for maintaining said side members in spaced parallel relation, when a tortional strain is exerted on the side member, the extremity of the page engaging a 65 finger having a rolled loop to engage between the pages and avoid injuring the pages.

In testimony whereof I affix my signature.
PAUL HORACEK.
